METHOD AND APPARATUS FOR ELECTROLYTIC COATING OF STRIP MATERIAL

Clarence J. Klein, Holliday's Cove, W. Va., assignor to National Steel Corporation, a corporation of Delaware

Application February 24, 1944, Serial No. 523,681

6 Claims. (Cl. 204—28)

1

This invention relates to the continuous coating of thin metal strip by electrodeposition and, in particular, to the application of a coating of protective metal such as tin or zinc to steel strip.

In one form of electrolytic strip-coating apparatus (such as that described and claimed in co-pending application Serial No. 487,758, now Patent No. 2,399,254, which E. W. Rieger and I filed on May 20, 1943), the strip is passed successively over a plurality of electrolyte pans and is subjected to numerous stages of electrodeposition in the several pans whereby a continuous coating of metal is eventually deposited onto the strip from anodes disposed in the pans. The number of pans required is considerable because it is convenient to coat one side only of the strip at a time, the preferred arrangement comprising two vertically spaced tiers of pans, one tier serving to coat one side and the other tier the other side, after the strip has been turned over. The delivery of electrolyte to such a large number of pans by means of pumps and supply and return pipe connections between them to the individual pans, presents a serious problem because of the complexity of the piping which would be necessary and the difficulty of accommodating numerous pipe lines in the available space.

I have invented a novel method and apparatus for coating strip whereby the supply of electrolyte to the several pans is greatly simplified, without impairing the effectiveness of the electroplating operation performed in each pan. In a preferred embodiment and practice of the invention, I mount the several electrolyte pans at progressively different elevations and provide suitable connections between adjacent pans to permit gravity flow of electrolyte from each pan to the adjacent, next lower pan. By this arrangement, electrolyte is initially delivered to the highest pan and flows therefrom downwardly through the remaining pans. Sufficient circulation of electrolyte is maintained to fill the several pans and permit an overflow of electrolyte therefrom into a collecting tank from which it may again be returned to the highest pan. In order to maintain the strip at the proper elevation relative to the surface of the electrolyte in the several pans and at the proper distance from the anode in each pan, I provide means in the form of pairs of rolls between adjacent pans, for changing the elevation of the strip by the same amount as the difference between the elevations of adjacent pans. These rolls may conveniently be the contact rolls by which electric current is supplied to the strip for electrodeposition.

2

The novel features and advantages of the invention may be clearly understood from the following detailed description which refers to the accompanying drawings illustrating the preferred embodiment and practice. In the drawings,

Figures 1A, 1B and 1C disposed side by side constitute a diagrammatic side elevation of an electrolytic coating line embodying my invention.

Figure 2 is a partial longitudinal section 10 through several electrolyte pans, with parts in elevation;

Figure 3 is a transverse section taken along the plane of line III—III of Figure 2; and

Figure 4 is a vertical section through the rolls 15 adjacent one of the housings therefor which is shown in elevation.

Referring in detail to the drawings, at the head of the coating line are provided uncoilers 10 and 11 to which coils of strip are delivered

20 from a conveyor 12, a crop shear 13 having pinch rolls, a seam welder 14 and delivery pinch rolls 15. A looping pit 16 accommodates a sufficient length of material to permit continuous travel of the strip through the apparatus subsequently

25 to be described, while allowing for the stoppage of the trailing end of a coil so it can be sheared and welded to the succeeding coil. From the looping pit the strip passes through a drag unit 17 and into an electrolytic cleaning tank 18 having deflector rolls 19 therein. In the tank 18 the strip is subjected to an initial electrolytic cleaning. It next passes through a scrubber 20 which mechanically removes most of the dirt and grease loosened by the electrolysis occurring in the tank

30 18. The strip next passes through a pickling tank 21 having deflector rolls 22 wherein the material is subjected to a pickling to remove traces of scale and prepare the surface for plating. The strip then passes through a second scrubber 23

35 which removes any solution remaining thereon from its passage through tank 21.

From the scrubber 23, the strip passes under a deflector roll 24 and between the first of a plurality of pairs of rolls 25 disposed at opposite

40 ends of a number of electrolyte pans. A plurality of pans 26 are disposed side by side in a lower tier and similar pans 27 are disposed side by side in an upper tier above the lower tier. Drip troughs 28 are located below the rolls 25 and a collecting tank 29 extends the full length of the two tiers. The pans 26 of the lower tier are disposed at progressively lower elevations going from left to right, i. e., the direction of travel of the strip. The strip is guided from the lower tier of pans 26 to the upper tier by deflector rolls

45 50 55

30. The pans 27 of the upper tier are positioned on progressively lower elevations going from right to left which is the direction in which the strip travels over these pans. It will be understood that first one side and then the other of the strip is subjected to repeated electroplating in passing over the pans of one of the tiers, the bottom surface of the strip being exposed to the electrolyte in both cases. Suitable electric connections extend from one roll of each pair 25 to a source of current and from the latter to anodes 31 (see Figures 2 and 3) disposed in the pans. As shown in the drawings, the anodes are supported on inclined guides 32 and 33. They are advanced progressively crosswise of the pans, the inclination of the guides serving to maintain substantially constant the spacing between the strip and the upper surfaces of the anodes as the latter are dissolved by the electroplating action. The anodes may be of tin if it is desired to coat the strip with that metal, or of zinc if a galvanizing treatment is to be effected.

From the upper tier of electrolyte pans, the strip passes over deflector rolls 34 and rolls 35 in a trough adapted to receive electrolyte dripping from the strip. It next passes under deflector rolls 36 in a rinse tank 37 and thence over rolls 38 above a drip pan 39. The strip then passes through a brushing apparatus 40, a hot rinse tank 41, a dryer 42 and over tensioning rolls 43 into a looping pit 44. The strip is drawn from the pit through drag unit 45 and a cut-out shear 46 by recoilers 47.

In order to provide for gravity flow of electrolyte from each pan to the next pan below, a pipe connection 48 extends between each pair of adjacent pans. Thus electrolyte supplied to the highest pan of the upper tier flows downwardly through the several pans 27 successively. A pipe connection may extend from the lowest pan 27 to the highest pan 26 so that the electrolyte, after flowing through all the pans 27, similarly traverses the several pans 26. Sufficient circulation of electrolyte is maintained to cause the several pans to fill and overflow slightly. The overflow is collected in the tank 29. Instead of the electrolyte flowing through all of pans 27 and 26, pipe connections (not shown) may extend from intermediate points to tank 29. Electrolyte may be pumped from tank 29 to the highest pan 27 and, if desired, to intermediate points, by means of any suitable pump and pipe connections. Branch connections 49 may be provided in some of the connecting pipes 48, in order to control the circulation as desired, by delivering a supplemental flow of electrolyte therethrough. Valves 48' and 49' are provided to control the rate of flow through the pipes 48 and 49.

As shown in Figure 2, the strip passing over each of the pans is maintained horizontal by the rolls 25 at opposite ends of the pan. In order to maintain the same position of the strip relative to the surface of the electrolyte and to the anodes in the several pans, I arrange the rolls 25 to deflect the strip downwardly as it passes from one pan to the next. The rolls 25 may be journaled in any suitable housings, such as that shown in Figure 4. The housing there illustrated comprises a frame 50 having ways 51 for a chuck 52 in which the upper roll 25 is journaled. The frame also has ways 53 adapted to receive a chuck 54 in which the lower roll 25 is journaled. It will be understood that a pair of housings is provided for supporting each pair of rolls 25. The housing frames rest on support-

ing members 55 extending across the coating line and are connected at their upper ends by a transom 56. The chucks 54 rest on springs 57. Adjusting screws 58 extend upwardly from the bottom of the frames 50 for supporting the springs. Screws 59 for adjusting the pressure of the rolls extend through the upper ends of the frames. It will be noted that the ways 51 and 53 are so disposed that the axes of the rolls 10 25 are displaced from each other horizontally. This relation of the rolls causes the strip to be deflected downwardly, as it passes from one tank to the next, as clearly as shown in Figure 2. The housings are designed so that the deflection 15 of the strip from one pan to the next is substantially equal to the difference between the elevations of adjacent pans.

As previously indicated, the rolls 25 are utilized for making electrical connections to the strip. 20 The upper roll 25 is preferably the contact roll, being composed of metal and having its surface in contact with the strip. The lower roll serves merely as a backing roll and preferably has its surface covered with rubber. A brush-holder 25 frame 60 is secured to but insulated from each housing frame 50 and is provided with brush holders 61, 62 and 63. The holders 62 and 63 are mounted on an upper cross member 64 of the brush holder which is pivoted to one of the 30 side members so it may be swung upwardly to permit the upper roll to be changed as may be necessary. Brushes in the holders 61, 62 and 63 have sliding contact with the necks 65 of the 35 upper roll 25. Bus bar connections 66 extend from the brush holder frames to the current source.

It will be apparent from the foregoing that my invention provides a highly advantageous method and apparatus for electrolytic coating in that the 40 supply of electrolyte to the numerous pans is greatly simplified by the provisions for gravity flow through the pans successively. This arrangement of the pans does not introduce any additional complications into the apparatus and 45 reduces to a minimum the number and complexity of the piping connections necessary to insure a suitable supply of electrolyte in each pan at all times. The arrangement of the rolls between 50 pans which serve as guide rolls as well as contact rolls, insures that the strip is maintained in the same relation to the surface of the electrolyte in each pan so that a uniform plating effect will be accomplished as any point on the strip travels over each pan. The arrangement 55 of rolls causes the strip to be flexed around a portion of the periphery of each roll. This results in better electrical contact of the strip with the upper roll and better frictional contact therewith to insure rotation of the roll when it 60 is not driven. The pans 26 and 27 may be progressively stepped up, in the direction of strip travel, instead of down, as shown. In that case the electrolyte will flow in a direction opposite that of strip movement, instead of in the same 65 direction, as in the arrangement illustrated.

Although I have illustrated and described but a preferred embodiment and practice of the invention, it will be recognized that changes in the arrangement and procedure disclosed may be 70 made without departing from the spirit of the invention or the scope of the appended claims. Obviously, the invention may be used for the coating of strip composed of metal other than steel and for the application of coating metals 75 other than those mentioned.

I claim:

1. Apparatus for progressively electroplating a continuously moving strip, comprising a plurality of pans across which the strip is passed successively in contact with electrolyte in the pans, said pans being spaced from each other horizontally and disposed side by side at progressively different elevations, each pan being adapted to contain electrolyte and having therein an electroplating anode, means for connecting the anode to a source of electroplating current, conduits directly connecting each pair of adjacent pans whereby electrolyte flows by gravity from one pan to the adjacent next lower pan, and strip guiding means in the spaces between adjacent pans for deflecting the strip downwardly as it passes from one pan to the next, said strip guiding means maintaining the strip horizontal in its passage through said pans and at a predetermined distance from the anode in each pan.

2. Apparatus for progressively electroplating a continuously moving strip, comprising a plurality of pans across which the strip is passed successively in contact with electrolyte in the pans, said pans being spaced from each other horizontally and disposed side by side at progressively different elevations, each pan being adapted to contain electrolyte and having therein an electroplating anode, means for connecting the anode to a source of electroplating current, conduits directly connecting each pair of adjacent pans whereby electrolyte flows by gravity from one pan to the adjacent next lower pan, and strip guiding means in the spaces between adjacent pans for deflecting the strip downwardly as it passes from one pan to the next in an amount substantially equal to the difference between the elevations of adjacent pans, said strip guiding means maintaining the strip horizontal in its passage through said pans and at a predetermined distance from the anode in each pan.

3. Apparatus for progressively electroplating a continuously moving strip, comprising a plurality of pans across which the strip is passed successively in contact with electrolyte in the pans, said pans being spaced from each other horizontally and disposed side by side at progressively different elevations, each pan being adapted to contain electrolyte and having therein an electroplating anode, means for connecting the anode to a source of electroplating current, conduits directly connecting each pair of adjacent pans whereby electrolyte flows by gravity from one pan to the adjacent next lower pan, and a pair of cooperating guide rolls having their axes displaced from each other horizontally in the spaces between adjacent pans for deflecting the strip downwardly as it passes from one pan to the next, said guide rolls maintaining the strip horizontal in its passage through said pans and at a predetermined distance from the anode in each pan.

4. Apparatus for progressively electroplating a continuously moving strip, comprising a plurality of pans across which the strip is passed successively in contact with electrolyte in the pans, said pans being spaced from each other

horizontally and disposed side by side at progressively different elevations, each pan being adapted to contain electrolyte and having therein an electroplating anode, means for connecting the anode to a source of electroplating current, conduits directly connecting each pair of adjacent pans whereby electrolyte flows by gravity from one pan to the adjacent next lower pan, and a pair of cooperating guide rolls having their axes displaced from each other horizontally in the spaces between adjacent pans for deflecting the strip downwardly as it passes from one pan to the next in an amount substantially equal to the difference between the elevations of adjacent pans, said guide rolls maintaining the strip horizontal in its passage through said pans and at a predetermined distance from the anode in each pan.

5. Apparatus for continuously and progressively electroplating a moving strip, comprising a plurality of pans disposed side by side at progressively different elevations presenting electroplating cells, each being adapted to contain electrolyte and having therein an electroplating anode, means for connecting the anode to a source of electroplating current, across each of which the strip moves from end to end in a horizontal path in contact with the body of electrolyte therein and at a predetermined distance from the anode in the cell, the paths across the cells being disposed at progressively different elevations corresponding to the elevations of the pans and being positioned to maintain the strip in substantially the same relation to the anode in all of the cells; strip guiding means positioned outside of and adjacent the ends of each pan in position to maintain the moving strip in the path across the cell; and conduit means directly connecting each two adjacent pans whereby electrolyte flows through the conduit from the higher pan to the lower pan of the adjacent pans.

6. In a method of electroplating strip, the steps including passing the strip successively in horizontal paths in contact with a plurality of spaced baths of electrolyte disposed side by side at progressively different elevations while maintaining said horizontal paths at substantially the same vertical distance from anodes located in the baths, and flowing electrolyte by gravity directly from each bath to the next adjacent lower bath while effecting electrodeposition on to the strip from the electrolyte in each bath.
